UNITED STATES PATENT OFFICE.

HENRY A. HERR, OF CHICAGO, ILLINOIS.

METHOD OF PREPARING PRINTING PLATES.

Original application filed January 2, 1923, Serial No. 610,212. Divided and this application filed March 17, 1923. Serial No. 625,701.

To all whom it may concern:

Be it known that I, HENRY A. HERR, a citizen of the United States, residing at Chicago, in the county of Cook and State of Illinois, have invented a certain new and useful Improvement in Methods of Preparing Printing Plates, of which the following is a specification.

This application is a division of my original application, Serial No. 610,212, filed January 2, 1923, and one of the objects of the present invention is to provide an improved method of preparing a printing plate by the use of the matrix, constituting the subject matter of the above referred to application.

The present invention has for a further object the use of such a matrix for raising the "solid" portions of the printing plate by operating from the back of the printing plate so that the "solids" on the printing surface will be elevated the desired height above the "high lights" or portions of the surface which are to be printed lighter than the "solid" portions, and at the same time obviate the danger of marring or injuring the printing surface of the plate.

To the attainment of these ends and the accomplishment of other new and useful objects as will appear, the invention consists in the features of novelty in substantially the herein described method of treating the printing plate as shown in the accompanying drawings illustrating a method or process of carrying this invention into operation.

In the drawing

Figure 1 illustrates the face of the printing or electrotype plate, which is to be treated with this improved method or process.

Figure 2 is a view of the obverse face of the matrix.

Figure 3 is a sectional view on line 3--3, Figure 1.

Figure 4 is a view of the reverse face of the matrix.

Figure 5 is a sectional view of the matrix, which is etched on both sides.

Figure 6 is a sectional view of the printing plate with the matrix placed against the back thereof.

Figure 7 is a sectional view of the print-

ing plate with the matrix applied to the back thereof and the face of the printing plate resting against a body or cushion.

Figure 8 is a sectional view showing the 55 operation of forcing the matrix into the back of the printing plate.

Figure 9 is a view of the completed printing plate, after the back thereof has been 60 smoothed.

In carrying this improved method into operation a relief or electrotype plate is employed having upon its front a picture or reproduction produced in any manner or by any process, certain portions of which designs or reproduction constituting "high lights" or portions to be printed light and other portions which constitute what is technically known as "solids" and which "solids" are to be printed heavier or darker 70 than the "high light" portions.

In the drawings, the numeral 15 designates a printing plate such as an electrotype or other suitable plate having produced upon its face in any ordinary and well-known manner the design or pattern 16 from which reproductions are to be made.

This design or pattern consists of portions 17 technically known as "solids" and which portions are to be printed heavier 80 than other portions 18, technically known as "high lights," it being understood that in the drawings the various figures are illustrated on an exaggerated scale.

In carrying this improved method into 85 operation, a matrix 19 is prepared in the manner as set forth in the application herein referred to, that is to say the matrix has etched on both faces thereof facsimiles of the design appearing in the face of the 90 printing plate 15, so as to produce or form elevations 20 and depressions 21 on both faces thereof, the elevations 20 corresponding with the "solids" on the face of the printing plate and the depressions 21 corresponding to the "high lights" portion or 95 portions on the printing plate which are printed lighter than the "solids."

This matrix is then placed against the back or reverse face of the printing plate 10 15, so that the depressions 21 will register with the "high light" portions 18 of the

plate 15 and the elevations 20 will register with the "solid" portions 17 of the printing plate 15.

The superposed plates are arranged upon a suitable mat 22, so that the printing surface of the plate 15 contacts with the mat. The mat rests upon a suitable support 23 and pressure is brought to bear upon the matrix 19 by means of a suitable plunger 24 with a mat 25 interposed between the plunger and the matrix 19 to force the matrix into the back of the printing plate 15.

This operation will cause predetermined portions of the printing surface of the printing plate to be displaced by the matrix to cause the "solid" portions of the printing surface to stand higher than the "high light" portions so that when transfers or impressions are made by the printing plate, the "solids" of such plate will print heavier than the "high light" portions.

The matrix is then removed and the back of the printing plate is smoothed in any ordinary and well known manner as shown in Figure 9, thereby adapting the plate to be mounted either upon a block or a bed or cylinder of a printing press.

With this improved method it will be manifest that the heretofore expensive "made ready" operation is dispensed with and the amount of labor necessary to cause the "solid" portions on the face of the printing surface to stand higher than the "high light" portions is materially reduced. Fur-

thermore, the operations of treating the printing plate are performed from the back of the plate, thereby obviating the danger of injuring or marring the printing surface of the plate.

It will also be manifest that this improved method or process is carried into operation and the "solids" on the plate are raised while the plate is outside of the printing or reproducing machine, with the result that the plates may be completed and then shipped or sold as an article of manufacture, so that all the user will have to do is to attach the same to the bed of the press without having to indulge in the laborious undertaking of preparing a "make ready" on his press.

What is claimed as new is:—

The method of treating printing plates which consists in placing against the back of the plate a matrix which has etched on both faces thereof registering facsimiles of the design appearing on the face of the printing plate and in a position that the designs on both faces of the matrix will register with the design on the face of the printing plate, and then applying pressure upon the matrix to displace predetermined portions of the printing surface of the said plate and from the back of said plate.

In testimony whereof I have signed my name to this specification, on this 14th day of March, A. D. 1923.

HENRY A. HERR.
